United States Patent Office

Des. 185,851
Patented Aug. 11, 1959

185,851

CHAIR

Trace Christenson and Wayne W. Good, Sturgis, Mich.,
assignors to Harter Corporation, Sturgis, Mich.

Application January 16, 1959, Serial No. 54,200

Term of patent 14 years

(Cl. D15—1)

Fig. 1 is a front perspective view of a chair embodying our invention.

Fig. 2 is a side elevational view.

Fig. 3 is a rear view, and

Fig. 4 is an enlarged cross-sectional view of one of the pedestal supporting members on a line corresponding to line 4—4 of Fig. 2.

The side not shown is a duplicate of the side shown in Fig. 2.

We claim:

The ornamental design for a chair, as shown and described.

UNITED STATES PATENT OFFICE

Certificate of Correction

Design No. 185,851

August 11, 1959

Trace Christenson et al.

It is hereby certified that error appears in the above numbered patent requiring correction and that the said Letters Patent should read as corrected below.

In the sheet containing the drawings and specification, Figures 1, 2, 3, and 4, should appear as shown below instead of as in the patent:

Signed and sealed this 19th day of January 1960.

[SEAL]

Attest:

KARL H. AXLINE,

Attesting Officer.

ROBERT C. WATSON,

Commissioner of Patents.
